UNITED STATES PATENT OFFICE.

ARTHUR J. BOLFING, OF SAN FRANCISCO, CALIFORNIA.

ROTARY ENGINE.

1,336,997.

Specification of Letters Patent. Patented Apr. 13, 1920.

Application filed August 9, 1918. Serial No. 249,103.

To all whom it may concern:

Be it known that I, ARTHUR J. BOLFING, a citizen of the United States, and a resident of the city and county of San Francisco, State of California, have made a new and useful invention—to wit, Rotary Engines; and I do hereby declare the following to be a full, clear, concise, and exact description of the same.

10 The invention relates particularly to rotary internal expansion engines.

Among the objects of the invention are to provide a true rotary engine adapted to use the expansive power of steam, compressed 15 air and like fluids. Other objects and advantages will appear as this description progresses.

In this specification and the annexed drawings the invention is illustrated in the 20 form considered to be the best, but it is to be understood that the invention is not limited to such form because it may be embodied in other forms, and it is also to be understood that in and by the claims following the description it is desired to cover the invention in whatever form it may be embodied.

In the accompanying two sheets of drawings,

30 Figure 1 is a perspective view of a rotary engine constructed in accordance with this invention, broken away in cross section on the line I—I Fig. 2 to illustrate the interior construction and arrangement 35 of the parts.

Fig. 2 is a side elevation of the same, the upper half of the engine above the axial line being shown in cross section.

Fig. 3 is an enlarged fragmentary detail 40 illustrating the manner of mounting and controlling the vanes.

Fig. 4 is an end elevation of the same in cross section taken on the line IV—IV Fig. 3.

45 Fig. 5 is a fragmentary detail illustrating the initial entrance of steam with respect to the vane.

In detail the construction illustrated in the drawings includes, the hollow shaft 1, 50 fixed in any suitable base such as the brackets 2 secured to a suitable foundation 3. The manner of mounting this shaft will vary with the application of the engine to

various uses; in the present case the base 3 represents the structure in the fuselage of 55 an air plane. The hollow shaft 1 is connected with a source of power, such as the steam service pipe 4, controlled by the throttle valve 5, operated by the handle 6. The outer end of the shaft 1 is closed by 60 the transverse wall 7 and terminates in the stud 8.

The stator or stationary element of the engine has a substantially elliptical perimeter 10 set eccentric to the axis of the 65 shaft 1; the perimeter 10 being parallel with the axis of this shaft, one segment of the perimeter from 11 to 12 (see Fig. 1) being concentric with the axis of the shaft and adapted to approximate contact with 70 the rotor or rotating element of the engine.

The rotor comprises a substantially cylindrical casing 13, having the lateral flanges 14—15 to which the side plates 16 and 17 are bolted (see Fig. 2). The hubs 18 and 75 19 of these respective plates are suitably machined to receive the antifriction roller bearing 20 and 21 respectively, interposed between the hubs of these plates and the shaft 1, and the stud 8, at opposite sides of 80 the engine, to provide suitable mountings for the rotary casing on its axial center, concentric with the axis of the shaft 1 about which it is free to rotate. The casing 13 is provided at circumferential intervals 85 with the sockets 22, in the present instance three in number, but this number may be increased or decreased in accordance with the number of phases or cycles it is desired that the operation of the engine 90 may pass through during each revolution.

The rotor is provided with the vanes 23, 24, 25 having cylindrical heads 26 adapted to snugly fit and oscillate within the sockets 22, forming a pressure tight contact there- 95 in. The bodies of these respective vanes are curved on radii equal to the radius of the casing so that they may lie against the inner perimeter of the casing concentric with the axis of the shaft 1, see vane 23 in Fig. 100 1. Their other ends are adapted to wipe against the perimeter of the stator forming a pressure tight contact therewith see vanes 24 and 25. The perimeter of the rotor is interiorly provided with the recesses 27, 105 28 and 29, of any desirable contour extend-

ing from in front of the ends of the vane and to a suitable distance to the rear thereof.

To insure the contact of the inner end 5 of the vanes against the perimeter 10 of the stator, I provide the torsion springs 30 confined within the hollow of the heads 26 of the vanes. The inner end 31 of the springs engages a hole 32 in the head 26, the 10 opposite end 33 of the spring engages a plug 34 rotatable within the sockets 22, and is provided with a suitable wrench stud 35 for rotating the plug, to increase or diminish the torsional tension on the spring 30, 15 the tension being fixed by the pin 36 in the plates 16 or 17 and engaging notches 37 in the plugs. The plug is covered by the cap 38 screwed thereover. The torsion of the spring 30, and the initial impact of the 20 steam against the vane tends to swing the vane inward against the periphery of the stator, to insure their contact therewith against centrifugal force, friction or any other causes liable to break the contact between the stator and the vanes. 25

The eccentric relation of the stator to the outer casing leaves a crescent shaped space between these members within the casing. It is the function of the vanes to divide this 30 space into cycles or phases representing intake, expansion and exhaust.

The inlet nozzle 40 communicates through the throat 41 with the hollow shaft 1, the outlet or mouth of the nozzle being closed 35 by contact with the interior perimeter of the casing and the vanes passing thereover, during the cutoff cycle or period. The nozzle of a rotary steam engine is a member in which the energy existing as heat in the 40 steam is converted into kinetic energy or energy of motion. This conversion, when properly carried out, is highly efficient, that is, the proportion of heat converted into work may closely approach the limiting 45 theoretical value. The cross section of the nozzle is determined by the pressure and quantity of steam to be passed and the amount of heat to be converted into work; it will therefore vary with certain 50 conditions. The cross section of the throat determines the quantity of steam that can pass with a given initial pressure. From the narrowest part to the outlet, the cross section increases in such a 55 way that as the steam continues to expand, there is an approximately uniform acceleration. In the case of water this enlargement of friction would be accompanied by a reduction of velocity. But when dealing 60 with steam there is a continual gain in the velocity of the steam particles and a decrease in density, pressure and temperature. In the present instance it is desirable to obtain impact of the steam against the vanes as well as to utilize its expansive effect; for

that reason the nozzle 40 is curved to approach as nearly as may be a tangential delivery at the periphery or outlet against the vanes, to avoid the production of acoustic vibrations and nodes of high and low pressure in the issuing jet. Such disturbances result in steam shock and in a reconversion of kinetic energy into heat, in such a way 70 that such heat is passed through the engine without doing useful work. To maintain the 75 acceleration of the steam issuing from the nozzle, the contour of the recesses 27-28-29 are so shaped as to present the least resistance to the flowing steam, compressed air or other fluid issuing from the nozzle. 80

To regulate the "cutoff," or the points at which the steam issuing from the nozzle is permitted to enter the casing, I provide the 85 slidable plates 43, 44, and 45, extending across the width of the casing 13, and following its concentric contour. Each plate is controlled by a wing nut 46, threaded onto a stud on the plate and jamming against the exterior perimeter 13 of the casing. For the sake of simplicity in illustration, this 90 elementary form of adjustment is shown. It is obvious, however, that these plates may be moved in unison by the addition of suitable mechanisms for that purpose.

Referring to Fig. 1, the mouth of the 95 nozzle 40 has just been cut off by the edge of the contiguous plate 43. The space A, between the stator, the rotor and the vanes 24 is being filled with expanding steam, which in seeking space within which to expand will advance toward the larger area B against the stator, thus pulling or rotating the casing to the right or clockwise as indicated by the arrow, until the vane 24 assumes the position in which the vane 25 is 100 shown, which is approaching the cycle of maximum expansion in the space B. At the point 10' in the perimeter of the stator 9 the space C between the stator and the rotor begins to contract, which is the exhaust 105 cycle, the contraction of the space reaching its maximum when the vane has assumed the position of the vane 23, forcing or squeezing the expanded steam through the ports 47 formed in the perimeter of the 110 stator between the cross bridge 48, that remain merely to give stability to the stator, and to guide the end of the vanes passing thereover. The exhaust or expanded steam, forced into the chamber 49 of the stator, 115 escapes through the crescent shaped space 50 surrounding the hollow shaft 1 and extending to the atmosphere or suitable condensers for reconversion to water, in accordance with the usual practice. The inner 120 surface of the vane 23 lying against the concentric portion 51 of the stator permits the passage of the vane 23 thereacross, meantime effectively sealing the escape of steam from the nozzle 40, also sealing the cycle A 125 130

in the operation of the engine. When the end of the vane 23 passes the opening or mouth of the nozzle 40, the steam escaping therefrom into the recess 29 therebehind, adding its force to the spring 30 operating against the vane, forces the edge of the vane against the perimeter of the stator as illustrated by the vane 24, the steam escaping into the recess and completely filling the space A, as previously described, until the succeeding plate 45 assumes the position illustrated by the plate 43 at which period the steam is again cut off and expands and exhausts as described.

Should it so happen that the engine should stop on a dead center such as represented in Fig. 1, after the throttle 5 was closed and no steam was issuing through the nozzle 40, it would be manifestly impossible to start the engine. To overcome this difficulty I provide the by-pass 52, communicating through the longitudinal hole 53 with a steam pipe 54, controlled by the valve 55, so that steam may be introduced into the space A past the check valve 56, for moving the rotor past the dead center until it attains sufficient momentum to carry it over this center in the succeeding revolutions. The check valve 56 prevents back pressure through the pipe 53.

The sides of the stator contact with the plates 16 and 17 and prevent leakage of steam at these points, all points of approximate contact between the stator and the rotor being effectively sealed, pressure tight, by the introduction of suitable lubricant with the steam in the usual manner. To further insure proper sealing, I introduce the laminated packing 57 and 58 on opposite sides of the engine adjacent to the bearings 20 and 21. Lost motion in the bearings 20 and 21 may be taken up by the running nuts 59, threaded on the shaft and jammed by the lock nuts 60 and 61 in the usual manner. These bearings are protected by the caps 62 and 63, the former fixed to the plate 16 and engaging the hollow shaft against which it is packed by the stuffing gland 64, for the purpose of retaining lubricant within the bearings. The cap 63 performs a similar function and is fixed to the plate 17 over the end of the shaft, like wise inclosing the bearing 21 for the purpose of retaining lubricant.

The relative position of parts shown in Fig. 5, illustrates the lifting action of the steam entering the recess 27, behind the end of the vane and forcing it against the perimeter 10 of the rotor, as indicated by the arrows.

Centrifugal force can be taken advantage of to maintain the contact between the vanes and the rotor, by the counterweight 30" fixed to the vane on the opposite side 65 of its pivoted center and projecting through

a slot in the rotor. The outward throw of the counterweights swinging the ends of the vanes inward, as shown in Fig. 5.

Modifications within the purview of this invention will suggest themselves to those skilled in the art in adapting it to special purposes.

Having thus described this invention, what I claim and desire to secure by Letters Patent is:

1. A rotary engine comprising a stator set eccentric to the axis of the engine and having a nozzle therein; a rotor inclosing said stator, concentric with said axis and circumferentially contacting with said stator and closing said nozzle, and having recesses therein; adjustable cutoff means interposed between said rotor and stator contiguous to said nozzle and said recesses; vanes interposed at intervals between said stator and rotor; and means for introducing an expansive medium through said nozzle, and exhausting it from between said vanes.

2. A rotary engine comprising a stator; a rotor inclosing said stator and having vane sockets therein; vanes having hollow heads pivotally engaging said sockets, with their opposite ends bearing against said stator; torsion springs within said heads having one end engaging said vane and the other engaging said rotor and adapted to normally hold said vanes in contact with said stator.

3. A rotary engine comprising a fixed hollow shaft; a stator on said shaft; a rotor inclosing said stator, set eccentrically thereto and circumferentially contacting therewith; curved vanes pivoted in said rotor and adapted to pass the contact between said rotor and stator; spring means within said vanes for normally holding the same in contact with the stator; perimetrical recesses in said rotor contiguous to said vanes, means for introducing an expansive medium ahead of said first mentioned inlet and an exhausting outlet of substantially the same width as the stator.

4. A rotary engine comprising a fixed hollow shaft; a stator eccentric on said shaft having a nozzle therein opening into said shaft and through the perimeter of said stator of substantially the same width as the stator; a rotor having perimetrical recesses and inclosing said stator concentric with said shaft and contacting with said stator contiguous to the outlet of said nozzle, curved vanes pivoted in said rotor and adapted to concentrically pass the said contact between said stator and rotor and extending over said recesses; means for introducing an expansive medium through said hollow shaft and nozzle; an auxiliary inlet for introducing an expansive medium ahead of said nozzle, and a suitably disposed

bridged chamber within said stator connected with means for exhausting said medium from the engine.

5. A rotary engine comprising a fixed hollow shaft; a stator eccentric on said shaft and substantially in perimetral contour and having a nozzle therein opening into said shaft and through the perimeter of said stator, a rotor having perimetrical recesses 10 and inclosing said stator, concentric with said shaft and contacting with said stator contiguous to the outlet of said nozzle; curved vanes pivoted in said rotor and adapted to concentrically pass the said contact between said stator and rotor and extending over said recesses; means for introducing an expansive medium through said hollow shaft and nozzle; said nozzle so shaped as to impart an impact as well 20 as expansive force to said expansive medium, an auxiliary inlet for introducing an expansive medium ahead of said nozzle and means for exhausting said medium from the engine.

25 6. A rotary engine comprising a rotor and stator; vanes pivoted in said rotor and bearing against said stator; means for introducing an expansive medium between said vanes comprising an inlet port extending substantially across the full width of the stator, an auxiliary inlet for introducing an expansive medium ahead of said first mentioned inlet and means for exhausting said expansive medium comprising a 30 port extending substantially across the full width of the stator and occupying approximately one fourth of the peripheral area of said stator.

40 7. A rotary engine comprising a fixed hollow shaft; a stator on said shaft; a rotor inclosing said stator, set eccentric thereto and circumferentially contacting therewith, curved vanes pivoted in said rotor and adapted to pass the contact between said 45 rotor and stator; perimetrical recesses in said rotor contiguous to said vanes; means for introducing an expansive medium between said vanes; an auxiliary inlet for introducing an expansive medium ahead of said first mentioned inlet; and an exhausting 50 outlet of substantially the same width as the stator.

55 8. A rotary engine comprising a fixed hollow shaft; a stator on said shaft; a rotor inclosing said stator, set eccentric thereto and circumferentially contacting therewith; curved vanes pivoted in said rotor and adapted to pass the contact between said 60 rotor and stator; perimetrical recesses in said rotor contiguous to said vanes; an inlet for introducing an expansive medium between said vanes adjacent said point of contact of the stator and rotor; adjustable cut-off means interposed between said rotor and

stator contiguous to said inlet and recesses 65 and means in said stator for exhausting said expansive medium.

9. A rotary engine comprising a fixed hollow shaft; a stator on said shaft; a rotor inclosing said stator, set eccentric thereto 70 and circumferentially contacting therewith; curved vanes pivoted in said rotor and adapted to pass the contact between said rotor and stator; perimetrical recesses in said rotor contiguous to said vanes; an inlet 75 for introducing an expansive medium between said vanes adjacent said point of contact of the stator and rotor; adjustable cutoff means interposed between said rotor and stator contiguous to said inlet and recesses 80 and means in said stator for exhausting said expansive medium; an auxiliary inlet for introducing an expansive medium ahead of said first mentioned inlet; adjustable cutoff means interposed between said 85 rotor and stator contiguous to said inlet and recesses and means in said stator for exhausting said expansive medium.

10. A rotary engine comprising a rotor and stator; vanes pivoted in said rotor; 90 spring means within said vanes for normally holding the same against the stator; means for introducing an expansive medium between said vanes comprising an inlet port extending substantially across the full width 95 of the stator; an auxiliary inlet for introducing an expansive medium ahead of said first mentioned inlet and means for exhausting said expansive medium comprising a port extending substantially across the full 100 width of the stator and occupying approximately one fourth of the peripheral area of the stator.

11. A rotary engine comprising a fixed hollow shaft; a stator on said shaft; a rotor 105 inclosing said stator, set eccentric thereto and circumferentially contacting therewith; curved vanes pivoted in said rotor and adapted to pass the contact between said rotor and stator; spring means within said 110 vanes for normally holding the same in contact with the stator; perimetrical recesses in said rotor contiguous to said vanes; an inlet for introducing an expansive medium between said vanes adjacent said point of contact of the stator and rotor; adjustable cut-off means interposed between said rotor and stator contiguous to said inlet and recesses 115 and means in said stator for exhausting said expansive medium.

In testimony whereof I have hereunto set my hand at San Francisco, California, this 27th day of July, 1918.

A. J. BOLFING.

In presence of—

A. J. HENRY,
BALDWIN VALE.
